UNITED STATES PATENT OFFICE.

DIXON L. BEAN, OF CHICAGO, ILLINOIS, ASSIGNOR, BY DIRECT AND MESNE ASSIGNMENTS, TO AMERICAN LAMP COMPANY, A CORPORATION OF ILLINOIS.

DESIGN FOR A LIGHTING-FIXTURE.

52,553.

Specification for Design.

Patented Oct. 15, 1918.

Application filed May 31, 1917. Serial No. 172,109. Term of patent 7 years.

To all whom it may concern:

Be it known that I, DIXON L. BEAN, a citizen of the United States, residing at Chicago, in the county of Cook and State of Illinois, have invented a new, original, and ornamental Design for a Lighting-Fixture, of which the following is a specification, reference being had to the accompanying drawing, forming part thereof.

The figure is a side elevation of a lighting fixture, showing my new design.

I claim:

The ornamental design for a lighting fixture, as shown.

DIXON L. BEAN.
